US0D1068290S

(12) **United States Design Patent** (10) Patent No.: **US D1,068,290 S**
(45) Date of Patent: ** Apr. 1, 2025

(54) **PATTERNED SHEET MATERIAL**

(71) Applicant: **CARTIER INTERNATIONAL AG**,
Steinhausen (CH)

(72) Inventor: **Kim Taeun**, Paris (FR)

(**) Term: **15 Years**

(21) Appl. No.: **35/519,436**

(22) Filed: **Sep. 19, 2023**

(80) **Hague Agreement Data**

Int. Filing Date: **Sep. 19, 2023**

Int. Reg. No.: **DM/232190**

Int. Reg. Date: **Sep. 19, 2023**

Int. Reg. Pub. Date: **Dec. 22, 2023**

(30) **Foreign Application Priority Data**

Mar. 24, 2023 (WO) WIPO130685

(51) **LOC (15) Cl.** **05-06**

(52) **U.S. Cl.**

USPC **D5/56**

(58) **Field of Classification Search**

USPC D5/53, 55, 56, 58, 59, 60, 61, 99

CPC D03D 15/25; D03D 15/65; D03D 15/67;
D03D 25/005; D03D 15/00

See application file for complete search history.

FOREIGN PATENT DOCUMENTS

EM 015041447-0003 * 11/2023

Primary Examiner — Karen S Acker

(57)

CLAIM

The ornamental design for a patterned sheet material as shown and described.

DESCRIPTION

1. Patterned sheet material

1.1 : Perspective

1.2 : Front

1.3 : Back

1.4 : Right

1.5 : Left

1.6 : Top

1.7 : Bottom

The broken lines in the reproductions depict portions of the patterned sheet material that form no part of the claimed design.

1 Claim, 7 Drawing Sheets
